BATHING SUIT

Edith M. Stenbeck, Manhattan Beach, Calif., assignor to Catalina, Inc., a corporation of California

Application December 7, 1955, Serial No. 39,185

Term of patent 3½ years

(Cl. D3—17)

Fig. 1 is a front perspective view of a bathing suit or similar article, showing my new design, and

Fig. 2 is a rear perspective view thereof.

I claim:

The ornamental design for a bathing suit or similar article, substantially as shown.
